GOLF ACCESSORY

Donnell W. Miller, Gering, Nebr.

Application December 9, 1936, Serial No. 115,011

2 Claims. (Cl. 273—33)

This invention is a golf accessory in the form of a device for use in aiding the golfer in guiding the club head toward the ball and also for use in protecting the ground from divots; and the invention together with its objects and advantages will be best understood from a study of the following description taken in connection with the accompanying drawing wherein:—

Figure 1 is a side elevational view illustrating 10 the application of the invention.

Figure 2 is a top plan view of the device and

Figure 3 is a transverse sectional view through the device.

Referring to the drawing by reference numerals it will be seen that the device comprises a narrow elongated strip 5 of metal or other suitable material.

Adjacent one end thereof the strip 5 is bent downwardly and tapered so as to provide an anchoring point 6 adapted to be imbedded, by the driving thereof, into the ground for anchoring the strip 5 in position.

At its relatively opposite end the strip 5 is notched as at 7 to accommodate the shank of a 25 golf tee 8.

From a point inwardly of the end 6 thereof and continuing to the inner end of the notch 7 the strip 5 has its opposite edge portions in sincipital relation as shown in Figure 3 to provide a 30 groove 8 extending along the longitudinal center of the strip from the inner end of the notch 7 to a point 9 on the strip. At the point 9 the strip has a dot, as shown in Figure 2, painted or otherwise provided thereon and distinguishably colored 35 from the strip 5.

The groove 8 will serve to strengthen the strip

while the dot 9 may be used for the purpose of aiding the player in guiding the club head toward the golf ball.

The strip 5 when used will thus serve as an aid to the golfer in improving his game and at the same time will serve to protect the ground from the divots or in other words, from being dug up as sometimes results from the head of the golf club striking the ground in advance of the ball.

It is thought that the utility and advantages of an invention of this character will be had without a more detailed description.

Having thus described the invention, what is claimed as new is:—

1. A golf accessory comprising an elongated strip having a pointed end bent at an angle thereto and provided as an anchoring device for the strip, said strip at its relatively opposite end being provided with a notch to accommodate the shank of a golf tee, said strip being also provided intermediate its end with an indicium for use by the golfer in guiding the club head toward the ball at the notched end of the device.

2. A golf ball accessory for use with a peg type tee and comprising an elongated strip of metal having a front end notched for the passage of the tee therethrough into the ground, and a rear hook-shaped sharpened end adapted to be driven into the ground to anchor said strip thereto at a point remote from the periphery of the ball, said strip adjacent its rear end having an indicium thereon and being transversely concave from said indicium to said notch to strengthen said strip.
